UNITED STATES PATENT OFFICE.

GEORGE W. CODDINGTON, OF HENO, OHIO.

MACHINE FOR MANUFACTURING WAXED OR COATED STRINGS.

SPECIFICATION forming part of Letters Patent No. 643,041, dated February 6, 1900.

Application filed June 17, 1897. Serial No. 641,164. (No model.)

To all whom it may concern:

Be it known that I, GEORGE W. CODDINGTON, a citizen of the United States, and a resident of the town of Heno, in the county of Butler and State of Ohio, have invented certain new and useful Improvements in Machines for the Manufacture of Waxed or Coated Strings, of which the following is a specification.

10 My invention consists of certain improvements relating to the machinery for manufacturing waxed tapers and coated strings, for which Letters Patent of the United States No. 303,984, dated August 26, 1884, were duly issued to me, and reference is hereby made to the said Letters Patent No. 303,984 for a full understanding of any portion of the herein-referred-to apparatus now treated as a part of the existing art and cursorily described in 15 this specification.

The several features of my invention and the various advantages arising from their use, conjointly or otherwise, will be apparent from the following description and claims.

20 In the accompanying drawings, making a part of this specification and in which similar letters of reference indicate corresponding parts, Figure 1, Sheet 1, represents in general a side elevation of a machine embodying my improvements. Fig. 2 is a side elevation of another portion of the mechanism. Fig. 3 is an edge view of the wheel shown in Fig. 2, and also of the power-pulley and the friction-flanges and disks, showing in elevation a 25 portion of the shaft on which these wheels are mounted. Fig. 4 is a side elevation showing the stripper-plate and the devices for adjusting that plate. Fig. 5 is a side elevation of the mechanism for keeping the composition 30 of the strings at the requisite temperature to enable them to be properly cut by the knife into desired lengths. Fig. 6 is a plan view of the clutch and gearing. Fig. 7 is an elevation of that part of the machine which lies to 35 the right of the plane through the dotted line 12 12 of Fig. 1. That face of the mechanism illustrated in this view, Fig. 7, is the one which faces toward the left in Fig. 1. Fig. 8 is an enlarged view of the guide through which the 40 strings pass and showing the conformation of those passages in the guide which admit the

strings. Fig. 9 is an enlarged side elevation of the feed and measuring mechanism.

Before proceeding to describe my improvements in detail I will give an outline of the mode in which the entire machine operates.

Balls A² of string A to be coated are first laid upon the table B. The strings A from their respective balls then pass up to the guide C. This guide C has as many passages C² through it as there are strings to be simultaneously coated, and each passage is connected to an open slot C³, running from it to the front edge of the guide C, so that the string can be inserted in the passage-way laterally, and thus obviate the necessity of running the string endwise through the passage-way. The preferred number of strings simultaneously coated is twenty-five. Each string passes up through its passage C² and over the rear edge of the guide C and then goes rearward and passes over a roll D and thence in a direction generally downward back and against roll D² and forth against roll D³ to cause the string to slightly resist a pull thereon and to prevent its bagging as it passes down through the composition wherewith the string is to be coated and which composition (technically called the "wax") is located in the tank E. The rolls D D² D³ are to be rotatable or stationary, as required, and are to be varied in number according to the resistance to be required. The tank E is suitably supplied with wax, preferably from the reservoir E², and the delivery of the liquid or semiliquid wax from this reservoir E² is regulated by a suitable device, the simplest and best one consisting of the plug or stopple E⁵, fitting into the floor of the reservoir E² and operated from above by a handle extended above the reservoir E². The strings A pass down into the composition and through stationary eyes E³, located in the tank, thence pass on near to the bottom of the tank E and then through stationary eyes E⁴, thence pass up past a device F, which draws from them the surplus wax, and then pass up into and through the device G for regulating the temperature and the consistency of the wax at the time it is to be cut. Thence the strings are brought together by a converging device H and are dried by the device J and are passed through a feed.

ing and measuring device K, composed of feed and measuring rollers K² K³, and are next presented to a cutting device L, whereby they (the strings) are cut into equal and given 5 lengths. These strings are then immediately upon being cut deposited in a box M, containing a given number of strings, and when the proper number of strings have been cut and deposited in the box the box is by mechanism N pushed to one side for delivering its 10 strings in a condition to be packed for the market.

I will now proceed to describe my improvements in detail. First, when a tangle occurs 15 in the string as it comes from the ball and before reaching the guide C, I provide the following - described mechanism, whereby the tangle stops the machine, viz: The ends of the guide-bar C respectively rest on the horizontal supports X X of the frame and have room to slide back and forth on said supports 20 between the stops X² X² and beneath covers or superincumbent strips connected to said stops. This guide C is connected to a frame C⁴ C⁴ C⁴, which extends rearward and is connected to one end of a lever C⁵, pivotally fulcrumed at C⁶ to the frame, and whose lower portion is provided with a hook C⁷ in position 25 when advanced to engage the nearest one of a number of pins or projections C⁸, located on a wheel C⁹, whose hub is interiorly a screw-thread, which latter engages a screw-thread P² on the main or power-transmitting shaft P. A power-pulley P³, driven in any suitable 30 way, is located on the shaft, so as to turn loosely thereon, and is between two friction-disks. One of these disks—viz., P⁵—is fixed 35 on the shaft, while the other, P⁶, is loose thereon. The power-pulley has friction-faces P⁴ 40 on each side, whereon the friction-disks can press when the pulley is clamped between the latter.

The operation is as follows: When the 45 devices are in usual working position and the strings are moving smoothly through the machine, the power-pulley P³ is tightly clamped between the friction-disks P⁵ P⁶. The wheel C⁹ is screwed tightly up against friction-disk P⁶, and thereby clamps the power-pulley P³ 50 between the friction-disks. This wheel C⁹ is revolving free of the hook C⁷, the latter and its lever occupying the position indicated by dotted lines in Fig. 2. As soon as a tangle is 55 present on a string A between its ball A² and the guide C and the tangle reaches the guide it catches its string moving on, draws the guide toward the lever C⁵, and thus moves the frame C⁴, which in turn moves lever C⁵ and causes its lower end to hook with a pin C⁸ of 60 the revolving wheel C⁹ and stops the latter from revolving. As the power-transmitting shaft P continues to rotate the latter is at once unscrewed from friction-disk P⁶ and disengages the clamps P⁵ P⁶ and allows the power- 65 wheel P³ to be out of engagement with the power-transmitting shaft P. Thus relieved, the wheel P³ will revolve and the mechanism

it heretofore turned, including the feeding device K, whereby the strings were drawn along through the machine, will stand still. 70 Opportunity is now given to the operator to take the tangle out of the string. As soon as he does this the machine is ready to be started. The operator now screws the wheel C⁹ against the power-wheel and the latter against the 75 friction-disk P⁵, and thereby clamps the power-wheel and puts the latter in engagement with the revolving power-transmitting shaft P. The power-transmitting shaft now again revolves and operates the machine and the latter again works smoothly. It is to be understood that as the operator screws up the wheel C⁹, as last aforementioned, the hooked end of lever C⁵ by its weight drops away from the wheel C⁹ and out of engagement with its pins, 80 leaving the latter free to be turned.

This improvement effects a great saving of time. Heretofore when a tangle caught the machine had to be stopped or the thread (string) would break, and after the machine 90 was stopped a new thread would have to be run often much of the way through the machine. The tangle would usually cause the string to break in the tank, and the broken string would then have to be fished out of the 95 melted wax in the tank by means of a hook and then followed and tied to the part from which it had been torn. This occupied much time, consumed much delay and loss of material, and in the meantime all hands would 100 have to be standing around waiting for the replacement to be made.

My present improvement in case of a tangle stops the machine and prevents breaking of the string. All that is required to be done is 105 to untie (get out) the tangle (knot) and screw up the wheel C⁹ and the machine goes right off again.

The location of the string-ball table A, as shown, is an improvement, as much more room 110 is obtained in which to properly operate the machine and to work than heretofore. There is also more opportunity to observe the string and detect a tangle.

The location of the mixing tank or pan (reservoir) E² above and partly back of the forward end of the tank E, as shown, is an improvement. This arrangement enables the operator to dispense with kettles and the laborious lifting and carrying of these to the 120 tank and filling the latter with wax from these kettles. It is to be understood that there are oil-lamps, steam-pipes, or other suitable heating apparatus beneath or in the tank E for keeping the wax hot, and consequently soft, 125 and also inside or under tank E².

The construction of the stopple is obviously 130 advantageous, the latter being of a conical form and fitting a conical hole (seat) in the bottom of the tank E.

Another improvement consists in the novel construction of the devices for stripping the extraneous wax from the string after being in tank E and emerging therefrom, carrying

a large amount of wax with it. This device (see Fig. 4) has the stripping-scraper F², fixed to a slide-plate F³, continually pressed forward by a spring F⁴. The latter is preferably a flat one of a bent form, one end of which bears against the frame-support Y and the other against the rear end of the slide-plate F³. The latter is held down and prevented from lateral displacement by means 5 of a set screw or screws F⁶, passing through a slot in the plate F³ and screwed into the support Y. What keeps the stripping-scraper F² at the correct distance from the axial centers of the waxed strings is the set-screws F⁶, 10 screwed through the fixed support F⁷. These set-screws F⁶ bear directly against the face of the scraper F² and when screwed forward hold the scraper farther back and allow the strings to carry more wax on with them, and vice 15 versa. The use of the scraper results in compelling the waxed strings to be of a uniform and a given size. Otherwise they would not be. It will be understood that the scraper F² is a long one and reaches and operates on all 20 of the twenty-five or more strings simultaneously. Two screws F⁶ make the entire adjustment. It will further be observed that the springs F⁴ keep the scraper always firm against the screws F⁶, and thus make the adjustment of the scraper F² entirely under the control of the screws F⁶.

Another feature of my invention relates to the construction of the devices G for keeping the wax of the strings at a proper temperature and degree of consistency for enabling them to be thereafter properly cut. This construction and its accompaniment construction is as follows: G² is a drum or roller having peripheral grooves in planes at right angles 25 to the axis of the roller and covered with a fabric, usually woolen-blanket stuff, (cloth.) The cloth sinks into these grooves and leaves them perceptible. The waxed strings run over this drum, and each one runs in a groove 30 in the drum, one for each string. The strings after running over the drum G² pass out over the roller or bar G³, whereby they are carried away from the drum and out of contact with it. The roller G³ is covered with woolen 35 blanket to absorb or wipe up any surplus moisture from the string as it takes them after leaving drum G² on their way to the cutting-knife. Beneath the drum G² is a water-tank G⁴ nearly full of water, and the lower 40 portion of the drum is submerged therein. An outlet-conduit G⁵ prevents the tank from overflowing.

G⁶ indicates a steam-pipe for supplying steam for heating the water in the tank. 45 G⁷ indicates a sprinkling-tube extending the length of the roller and above the latter. This tube is provided with the orifices G⁸, from which the water issues and falls upon the strings to cool them as they pass over the 50 roller. In practice the spray-jets are inclined toward the rear end of the roller, substantially as shown. A hood G⁹ is preferably

present over the tube G⁷ to confine any scattering portions of the spray within the proper limits. A rod G¹⁰ in front of the spray-tube 70 carries a piece of blanket G¹², the lower end of which drags on the upper face of the drum and prevents the water from the spray from running back and down the wrong (front) side of the drum. A rod G¹³ at the rear of the 75 spraying-tube carries a blanket G¹⁴, the lower end of which drags on the drum and assists in distributing the water over the waxed strings as they lie on the drum. A rod G¹⁵ holds this blanket down and causes it to more 80 fully press against the drum and waxed strings. The water to supply the spraying device may be drawn from any suitable source. A feed-pipe may be present connected to the spraying-tube G⁷ and adapted to receive the 85 end of a hose stretched over it. In very warm weather the use of cool water from the spray is necessary to keep the wax of the strings from running and render it hard enough to be cut by the knife. This spray 90 of cold water will be needed for a much longer period of the year where the apparatus is in a room and near a steam-boiler, &c., as is usually the case when the machine is operated by an engine. In cold weather warm 95 water may be applied through the spraying device. The steam-pipe G⁶ may be present to warm the water in the tank (in cold weather) and also to thaw this water when it happens to be frozen.

The drum G² is suitably rotated. In the present illustrative instance it is rotated by means of a sprocket-wheel H² on the shaft of this drum, and a sprocket-wheel H', fixed on the power-transmitting-shaft P, and a 105 drive(sprocket) chain H³, engaging the wheels H' and H².

My next improvement relates to the feed and measuring devices. The roll K² is the feed and measuring roll. It is a feed-roll, 110 because it is positively driven, and, in connection with the companion roller K³, draws the waxed strings along through the machine and delivers them to the cutting apparatus to be cut into lengths. The journals 115 of the companion roll K³ are in bearings K⁶, sliding in slotted openings and pressed toward the journals of the roll K² by means of springs K⁷, and the latter are compressed against the journal, preferably by means of 120 two set-screws K⁸, one on each end of roller K³, screwed through the frame Z. The degree of pressure exerted by the spring K⁷ against the journals of the roll K³ can be 125 regulated by turning the set-screws K⁸, and thus the pressure of the rolls K³ and K² upon the waxed strings as the latter pass between them can be varied as required. Thus the waxed strings can at all times be prevented from slipping between these rollers K² and K³, and these rolls will always feed the strings 130 forward at all times when the machine is at work.

The roller K² is driven from the power-

shaft P in such a manner that when this roller has rolled off a given length of strings, the knife advances and severs these strings from the remainder of the length. Usually 5 the circumference of the roller K² will equal the length of the strings to be cut.

L indicates the cutting device as seen in Fig. 1.

There is a sprocket-wheel P⁸ fixed on the 10 main shaft P and a sprocket-wheel K⁵ fixed on the shaft K⁴ of the roller K². These sprocket-wheels are connected by a sprocket-chain P⁷. Thus the roller K² is rotated.

On the shaft K⁴ is a fixed gear-wheel K⁶, 15 having a desired number of cogs, as twenty-five, and this gear-wheel K⁶ meshes with gear-wheel N, having a given number of teeth, as one hundred. Thus four revolutions of the gear-wheel K⁶ are made to one of wheel N, 20 and four sets of twenty-five strings cut in equal lengths have been cut and deposited in the delivery-box by the time the wheel N has made one revolution. The wheel N at each revolution—viz., at the time when one hundred 25 strings have been deposited in the delivery-box M—works a device for shoving out the boxes of strings. This device for shoving out the strings is already described and covered in and by previous Letters Patent 30 granted to me.

The location of the fan—in the present instance at the rear of the machine and facing the waxed strings, so as to cool them as they descend in readiness to be cut—is a great improvement. Heretofore I located the fan at 35 the front of the strings—viz., to the right (see Fig. 1) of the strings as they ascend.

These various features of improvement obviously add greatly to the efficiency of the machine and increase the facility of its operation 40 fully double the former capacity.

Before proceeding to specify what I claim I will briefly describe the means for operating the drying mechanism. The drying device 45 consists of the gear-wheel T⁶, meshing with the gear-wheel P³ and fixed upon shaft T⁴, duly journaled in the frame and carrying at its other end a pulley T³, which through the agency of a pulley-band T² operates pulley 50 T¹, fixed upon shaft T. Upon this shaft T is also fixed a pulley J', connected by a band with pulley T³ aforementioned, which operates the drying device. This latter mechanism comprises no part of my invention claimed 55 hereinafter.

What I claim as new and of my invention, and desire to secure by Letters Patent, is—

1. In a string-coating machine, the combination of the laterally-moving guide C, having 60 openings C², and bearings for enabling the guide to move laterally, and the rod C⁴, lever C⁵, a hook C⁷ on its lower end, and the wheel C⁹ having pins C⁸ for engagement with hook C⁷, power-wheel P³, having friction sides, friction-plates P⁵ and P⁶, one on each side of the

wheel P³, shaft P on which said wheels C⁹ and P³ and the friction-plates are located, the plate P⁵ being fixed to the shaft, and plate P⁶ being loose thereon, the shaft P being in part screw-threaded and engaging a screw-thread 70 in the hub of wheel C⁹, substantially as and for the purposes specified.

2. In machinery for coating strings, the tank, a stripper, for the strings as they come from the tank, comprising the elastically- 75 pushed plate F³, flange F² thereof, spring F⁴, stationary abutment, screw-rod F⁶ operated therefrom and bearing against the stripper-flange in opposition to the spring F⁴, substantially as and for the purposes specified. 80

3. In machinery for coating strings, the combination of the table Y, stripper-plates F², F³, having two slots, two hold-downs F⁵ thereof, two springs F⁴ for pressing the stripper-plate toward the strings, and the opposing set-screws F⁶, bearing on the stripper, and the supports F⁷, in relation to which the screws are adjustable, substantially as and for the purposes specified. 85

4. In machinery for coating strings, the 90 combination of the roller G², spraying device above, and blanket strip G¹² lying on the roller at rear of the spraying device, substantially as and for the purposes specified.

5. In machinery for coating strings, the 95 combination of the roller G², spraying device above, blanket strip G¹² dragging on the roller at rear of the spraying device, and blanket strip G¹⁴ dragging on the roller, in front of the spraying device, substantially as 100 and for the purposes specified.

6. In machinery for coating strings, the combination of the roller G², spraying device above, blanket strip G¹² dragging on the roller at rear of the spraying device, and 105 blanket strip G¹⁴ dragging on the roller in front of the spraying device, and the rod G¹⁵, for depressing the last-named blanket, substantially as and for the purposes specified.

7. In machinery for coating strings, the 110 combination of the rod G¹³, blanket strip suspended therefrom, the roller G² related to the tank and on which this blanket strip can drag, and the tank G⁴, and the conduit G⁶ for heating the water, substantially as and for 115 the purposes specified.

8. A device for regulating the temperature of the coating of the strings, and consisting of the felted grooved roller G², spraying device above, blanket strip G¹², and blanket 120 strip G¹⁴, and roller G¹⁵, in contact with the latter, and tank G⁴, receiving the lower part of the roller, conduit G⁶ entering the tank, and roller G³ for keeping the strings from the roller, substantially as and for the purposes 125 specified.

GEO. W. CODDINGTON.
